UNITED STATES PATENT OFFICE.

HEBRON B. LAYMAN, OF NEW YORK, N. Y.

INTERNAL-COMBUSTION ENGINE.

1,144,421.

Specification of Letters Patent. Patented June 29, 1915.

Application filed June 27, 1914. Serial No. 847,584.

To all whom it may concern:

Be it known that I, HEBRON B. LAYMAN, a citizen of the United States, and residing at New York, in the county of New York and State of New York, have invented certain new and useful Improvements in Internal-Combustion Engines, of which the following is a specification, such as will enable those skilled in the art to which it appertains to make the use the same.

This invention relates to explosion or internal combustion engines, and particularly to engines of this class of the sleeve valve type, and the object thereof is to improve the water circulating system or means by which the cooling water is circulated, and the method of circulating said water, so as to obtain or insure the lowest possible temperature at the point where the cylinder and cylinder head are ordinarily heated to the highest degree in the operation of the engine, so as to prevent the overheating of such parts and also the overheating of the valve which controls the inlet and the exhaust of the cylinder head; a further object being to facilitate the operation of the valve, and with these and other objects in view the invention consists in the construction, combination and arrangement of parts and the method of, and means for circulating the cooling water hereinafter described and claimed.

The invention is fully disclosed in the following specification, of which the accompanying drawing forms a part, in which the separate parts of my improvement are designated by suitable reference characters in each of the views, and in which:

Figure 1 is an end view of an engine of the class specified provided with my improvement; and, Fig. 2 a transverse section through one cylinder of the engine, any desired number of which may be employed, said view being on an enlarged scale.

In the practice of my invention, as shown in the drawing, I provide a cylinder *a*, in which is placed a piston *b* and the cylinder *a* is provided with an explosion head *a²*, the reference character *a²* also indicating the explosion chamber, and the explosion head *a²* is inclosed by an annular valve casing *a³* having an annular valve chamber *a⁴* in which is placed a sleeve valve *c*. The cylinder *a* and its explosion head, including the valve casing *a³* are inclosed by a main outer

casing or jacket *a⁵*, the top portion of which is enlarged as shown at *a⁶* to form a chamber *a⁷* in which the inlet and exhaust manifolds *a⁸* and *a⁹* are located, and said inlet and exhaust manifolds *a⁸* and *a⁹* are provided with radial passage-ways *a¹⁰* and *a¹¹* which extend inwardly through the outer and inner walls of the valve casing *a³* and communicate with the explosion chamber in the head *a²* of the cylinder, which form inlet and exhaust ports or passages which are controlled by the valve *c* in the usual manner.

In the construction shown all the parts above described with the exclusion of the cylinder *b* and valve *c* and designated by the reference characters *a*, *a²*, *a³*, *a⁴*, etc., are preferably formed integrally, as shown, but said parts or some of them may be formed separately, if desired, and the casing or jacket *a⁵* is provided with a separate and removable cover *d* connected therewith at *d²*, and forming a chamber *d³* having a bottom *a¹²* formed integrally with the casing or jacket member *a⁶*, and the valve casing *a³*, and the bottom *a¹²* of the chamber *d³* forms the top wall of the chamber *a⁷* in which the manifolds *a⁸* and *a⁹* are located.

The valve chamber *a⁴* is provided with inner and outer lining sleeves *e* and *f*, between which the valve *c* is movable, and the use of these sleeves enables the valve chamber *a⁴* to be cast in the operation of casting the cylinder *a* and connected parts, and all that is necessary to finish the space or chamber in which the valve *c* moves is to properly machine or finish the said lining sleeves *e* and *f*, and this is a much cheaper and much more effective operation, than any attempt to cast the valve chamber *a⁴* of proper dimensions and afterward machine or finish said chamber would be.

The manifolds *a⁸* and *a⁹* are provided with the usual inlet and outlet *a¹³* and *a¹⁴* and between the explosion head *a²* of the cylinder and the valve casing *a³* is an annular water passage or chamber *g* which communicates with a chamber *g²* in the top of the explosion head, and a pipe *g³* is passed down through the top of the cap *d* and into the top of the explosion head of the cylinder and communicates with the chamber *g*—*g²*, and the pipe *g³* opens upwardly into a passage-way *h* at the top of the engine and which applies to all the cylinders of the engine, and the pipe *h²* communicates with

the passage-way h at one end thereof and with a pump h^3 operated by the main crank shaft i of the engine and into which water from the radiator is admitted at i^2 .

- 5 Between the main outer casing a^5 — a^6 and the cylinder and its explosion head is a water chamber or passage k which incloses the manifolds a^8 and a^9 , and a pipe m passes through the cap d and communicates with said chamber and at its upper end said pipe communicates with a passage-way m^2 which extends longitudinally of the engine and which also communicates with the radiator as does the passage-way h .

- 15 In the accompanying drawing, the radiator and its connections are not shown for the reason that they form no part of my invention and, in practice, the means or apparatus for operating the valve c is placed in the
20 chamber d^3 , and this apparatus which also forms no part of this invention is not shown.

It will be seen that the water passage or chamber which incloses the explosion head of the engine and the water chamber or passage k are placed in communication at the bottom of the valve casing a^3 , as shown at n , and around this communication the top of the cylinder a is provided with an upwardly directed deflecting shield n^2 . The water

- 30 directed deflecting shield n . The water chamber or passage k is provided at or near the bottom thereof with an inlet o which, in practice, is placed in communication with the radiator and water from the radiator enters the chamber or passage-way k at o^2 and

35 flows upwardly through said chamber or passage, and around the manifolds a^8 and a^9 and out through the pipe m into the passage-way m^2 as indicated by the arrows x , and at the same time water is forced by the

40 pump h^3 through the pipe h^2 down through the pipe g^3 into and through the water passage or chamber $g—g^2$ and out beneath the valve casing a^8 , as indicated by the arrows y , and these separate flows of water are united

45 at p , and the water that flows in as indicated by the arrows y and under the control of the pump h^3 passes off through the pipe m and passage-way m^2 to the radiator with the water that enters through the inlet o and flows through the chamber or passage k , as indicated by the arrows x .

50

55 as indicated by the arrows α . It will thus be seen that I provide two different systems of water circulations, one being what is known as the thermo-siphon system and the other a pump system, and above the point where the two separate flows of water are connected at the bottom of the valve casing there is a downward and inward flow and an upward and outward flow.
60 56 In other words, there is a downward flow through the explosion head on the inner side of the valve casing, and an upward flow on the outer side of said head and on the outer side of said valve casing, and below the explosion head there is a continuous flow up-
65

wardly around the cylinder, and by means of this construction and system of water circulation, the engine is kept at the lowest possible degree of temperature at the point or points where the parts thereof are most apt to become overheated in use, said points being the explosion head and the parts surrounding and inclosing the same and the part of the cylinder adjacent thereto. 70

Where the thermo-siphon system of circulating water only is employed, the difference between the temperature of the water at the bottom of the cylinder and that around the explosion head and valve casing may be so great as to cause the sticking of the cylinder and the valve, but this trouble is largely, if not, entirely obviated by my improvement; and by means of my improvement, I may also use a smaller radiator for the reason that the difference in the temperature of the water as it leaves the radiator and when it returns to it will not be so great as when the thermo-siphon system of water circulation only is employed, and with my improvement the water that is pumped downwardly through the explosion head and which is turned in an upward direction where it unites with the upward flow of the thermo-siphon system also aids in moving the water of said system upwardly and outwardly through the upper part of the chamber or passage-way *k* and through the pipe *m*. The sleeve linings *e* and *f* are provided, in this form of construction, with shoulders which rest on the tops of the inner and outer walls of the valve chamber, but said linings may be supported in, or secured in said valve chamber in any desired manner, and the outer lining *f* is provided, in the construction shown, with slots or openings *f*² through which, in practice, the valve operating mechanism is connected with the valve, and in the construction shown the outer sleeve lining *f* is extended upwardly above the top of the valve casing, while the inner sleeve lining *e* terminates just above said valve casing.

terminates just above said valve casing. In the construction herein shown and described, the valve casing a^s and the valve c are above and beyond the limit of the movement of the piston but this is not necessarily so, and said valve casing and valve may be made larger and extended lower, if desired, and the transverse dimensions of the valve casing and valve may also be varied, and other changes in and modifications of the construction herein described may be made, within the scope of the appended claims, without departing from the spirit of my invention or sacrificing its advantages. 115 120 125

Having fully described my invention, what I claim as new and desire to secure by Letters Patent, is:—

1. An explosion engine provided with a cylinder having an explosion head, a sleeve 130

valve chamber provided with a sleeve valve which controls the inlet and exhaust ports of said head, said cylinder and valve casing being inclosed by a water chamber or 5 passage through which water flows upwardly on the outer side of the cylinder and valve casing, and the explosion head being provided with a water passage or chamber which communicates with the first 10 named water passage or chamber below the valve casing and through which water flows downwardly through said explosion head and on the inner side of the valve casing.

2. An explosion engine provided with a 15 cylinder having an explosion head inclosed by an annular valve casing having a sleeve valve, and means for passing water upwardly around said cylinder and said valve casing and other means for passing water 20 downwardly through the explosion head and on the inner side of the valve casing, the separate currents of water being united below the valve casing.

3. An explosion engine provided with a 25 cylinder having an explosion head inclosed by an annular valve casing in which is mounted a sleeve valve which controls the inlet and exhaust ports of the explosion head, and means for passing a current of 30 water upwardly around the cylinder and the valve casing and another current of water downwardly through the explosion head and on the inner side of the valve cas-

ing, said separate currents of water being united at the bottom of the valve casing. 35

4. An explosion engine provided with a cylinder having an explosion head inclosed by an annular valve casing in which is mounted a sleeve valve which controls the inlet and exhaust ports of the explosion 40 head, and means for passing a current of water upwardly around the cylinder and the valve casing and another current of water downwardly through the explosion head and on the inner side of the valve casing, said separate currents of water being 45 united at the bottom of the valve casing at which point the last named current is also directed upwardly.

5. An explosion engine provided with a 50 cylinder having an explosion head inclosed by an annular valve casing having a sleeve valve, and means for passing water upwardly around said cylinder and said valve casing and downwardly through the valve 55 casing, the separate currents of water being united below said valve casing.

In testimony that I claim the foregoing as my invention I have signed my name in presence of the subscribing witnesses this 60 25th day of June, 1914.

HEBRON B. LAYMAN.
